(57) **CLAIM**

The ornamental design for an air control box, as shown and described.

DESCRIPTION

FIG. 1 is a front top right perspective view of an air control box, showing our new design.

FIG. 2 is a front top left perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines showing in the figures illustrate unclaimed portions of the air control box and form no part of the claimed design.

1 Claim, 7 Drawing Sheets

FIG. 2

FIG. 3

FIG. 4

FIG. 6

FIG. 5

FIG. 7

FIG. 8
